UNITED STATES PATENT OFFICE.

HERBERT HARRY DUKE, OF NOTTINGHAM, ENGLAND.

BUCKLE FOR WRIST-WATCH STRAPS AND THE LIKE.

Application filed February 9, 1923. Serial No. 617,975.

To all whom it may concern:

Be it known that I, HERBERT HARRY DUKE, a subject of the King of Great Britain, residing at 116 Lenton Boulevard, Nottingham, in England, have invented Improvements in Buckles for Wrist-Watch Straps and the like, of which the following is a specification.

This invention relates to improvements 10 in buckles for straps and has particular though not exclusive reference to buckles used on straps for wrist watches and the like.

The principal object of this invention is 15 the provision of means for preventing a strap from becoming accidentally or inadvertently unbuckled and a further object amongst others is the provision of means for effectually covering the point of the buckle 20 prong or tongue, where such tongue is provided.

The principal feature of the present invention consists in the provision of a movable or removable cover member which 25 when the strap is in the fastened or buckled position is adapted to effectually prevent such strap from leaving the buckle prong or tongue and becoming unbuckled.

For the purpose of more fully describing 30 the nature of this invention reference will now be made to the accompanying drawings, wherein:

Fig. 1 illustrates in plan a strap with buckle according to the present invention, 35 such buckle being shown in the fully closed position.

Fig. 2 is a perspective view on an enlarged scale of the buckle shown in Fig. 1, the buckle cover being shown raised.

Fig. 3 illustrates in perspective a modified construction of buckle with cover opened.

Fig. 4 illustrates in perspective a further embodiment of the invention.

Fig. 5 is a detail section on line A—A of 45 Fig. 4, showing the spring removed.

Fig. 6 is a detail section on line A—A of Fig. 4, showing spring in position.

In one embodiment of this invention as 50 shown in Figs. 1 and 2 a cover member 1 is hingedly connected to the frame 2 of the buckle and is adapted when the strap 3 is fastened, to bear on or cover that portion of the strap 3 passing through the buckle, there being provided means for retaining 55 the cover 1 in its placed position and means

for rotating same to allow of the strap being unfastened.

Conveniently the frame 2 may be of rectangular configuration, one of the sides thereof forming the pivot or hinge 2^a for 60 the cover member 1.

Preferably the four sides of the frame are integral with one another or only three sides may be integral and a hole formed at the requisite position in two of said sides 65 for the accommodation of the hinge pivot, such hinge after being assembled with the cover being retained in any suitable manner.

In the application of this invention to buckles furnished with a cross member 4 70 which carries the prong or tongue 5, the cover 1 may be hinged at the end of the tongue 5 when the strap 3 is fastened.

Alternatively if the tongue or prong is carried by an end member of the frame (as 75 shown in Fig. 3) the cross bar 4 being provided, then the cover 1 may be conveniently hinged to one of the side members of the frame, such latter members being parallel with the length of the strap. 80

For the purpose of retaining the cover in its placed position when the strap is fastened projections may be conveniently formed on said cover 1 and such projections adapted to be accommodated within corresponding recesses in one of the frame sides. In the arrangement shown in Figs. 1 to 3 a lip 6 is formed on the cover 1 at that end remote from the hinge 7 and adapted to bear on that side 2^b of the frame remote from said hinge, projections 8 of hemi-spherical configuration being formed on said lip 6 and being accommodated within corresponding recesses 9 on said frame side 2^b. 90

Manipulation of the cover is conveniently effected manually and a projection 10 is preferably formed on the lip 6 for enabling disengagement thereof with the frame 2. 95

The tongue or prong 5, or the point thereof is conveniently accommodated within a 100 suitable recess 11 or the like formed in the cover 2.

In the modified arrangement shown in Figs. 4 to 6 inclusive, that bar 2^b of the frame 2 remote from the hinge 2^a is formed 105 on its front face with two elongated recesses 12 (Fig. 5) the outer end of each recess 12 being preferably deepened as at 13 these recesses being adapted to accommodate a spring having a bow shaped central por- 110

tion 15 and small cranked ends 16, the latter entering the deeper recesses 13. The spring is retained in position by burring over the metal of the frame bar 2^b at the 5 mouth of recesses 12. The hinge cover 1 is provided with a hollow projection 7 into which the spring 14 enters when the cover is closed so as to retain said cover in the closed position.

10 It will be appreciated that the buckle can be of varied sizes, and the shape thereof modified in many ways. Also, a plurality of prongs 5 may be incorporated.

15 I am aware that prior to this invention it has been proposed to hingedly mount a cover member on buckle frames, such cover having flanges depending therefrom engaging with the sides of the frame, and I make no claim thereto, but what I do claim and desire to 20 secure by Letters Patent is:—

1. In buckles for straps and the like, the combination of a buckle frame and a cover member hingedly mounted thereon, said cover member having a downwardly depending flange located at the end remote from the hinge, said flange and one end member 25 of the frame each having co-operating fas-

tening means for retaining the cover in closed position.

2. In buckles for straps and the like, the 30 combination of a buckle frame having a prong and a cover member hingedly mounted thereon, said cover member having a downwardly depending flange located at the extremity thereof opposite from the hinge, 35 said flange having projections adapted to engage recesses in one end bar of the frame and said cover having a recess for accommodating the point of the buckle prong.

3. In buckles for straps and the like, the 40 combination of a buckle frame having a prong and a cover member hingedly connected thereon, said cover member having a downwardly depending flange located at the 45 end thereof remote from the hinge, a curved spring carried on the outer face of one end member of the frame, said flange having a recess for engaging said spring and said cover having a recess for accommodating the point of the buckle prong.

HERBERT HARRY DUKE.
